ATTORNEY.

UNITED STATES PATENT OFFICE.

ADELBERT CHANDLER, OF AVONDALE, MISSOURI.

GRAIN-DOOR PULLER.

Application filed January 21, 1925. Serial No. 3,760.

To all whom it may concern:

Be it known that I, ADELBERT CHANDLER, a citizen of the United States, residing at Avondale, in the county of Clay and State 5 of Missouri, have invented certain new and useful Improvements in Grain-Door Pullers, of which the following is a complete specification.

This invention relates to grain door pullers or devices of a similar nature used for removing grain doors from cars of loaded grain.

The primary object of this invention is the provision of a means for effectively engaging the grain door and applying the necessary pressure thereto for dislodging said grain door from its position. It is well known, and a recognized fact, that the removal of grain doors from loaded grain cars is an exceedingly difficult job, especially where it is desired to remove the grain door without breaking or splitting the same and thus rendering it valueless for future use.

A further object of this invention is to provide a cheap and easily constructed means for carrying out its purpose, and to provide a device which will be effective, strong, easy to operate and not likely to get out of order.

With these general objects in view, the invention will now be described by reference to the accompanying drawing in which,

Fig. 1 is a side elevation of the grain door puller showing it in position with a grain door and illustrating the means by which a lifting power is imparted thereto after the device is placed in position.

Fig. 2 is a top plan view of the grain door puller, the lifting chain being broken away for clearness.

Fig. 3 is an end view of the device showing the manually operable handle and a striking head of the door engaging means.

Fig. 4 is a view of the opposite end of the device and,

Fig. 5 is an enlarged perspective detailed view of the bifurcated end and roller of the operating lever.

Referring at this time to the drawings in detail wherein similar reference characters refer to like parts throughout the several views and wherein 6 is the well known door post of the ordinary box car door and 7 the grain door which bears thereagainst when the car is filled with grain.

It is always desired to remove these grain doors 7 from the cars without splitting or breaking the same. Heretofore an ordinary crow-bar or similar implement has 60 been used for prying the door out of position.

This invention contemplates the use of a highly desirable device for effectively removing these doors without mutilating the 65 same. In the preferred form, it consists of a bar 8 having a shoulder 9 at its one end for engaging the upper edge of the grain door. A depending flange 10 integral with shoulder 9 secures this grip against slipping 70 by pressing against the back face of the grain door 7. Bar 11 positioned in vertical alignment below bar 8 is adapted to co-operate in the gripping of door 7 by having a spur 12 at one end for engaging said door at a 75 point adjacent the lower edge and below shoulder 9. The other end of bar 11 is provided with a striking surface 13 which may be used to force spur 12 into secure engagement with door 7. Bars 8 and 11 are connected by a pair of forward links 14 which engage each side of said bars and are pivotally connected thereto by pintles 15 and 16. Links 14 should be connected to bar 11 immediately behind spur 12 and to 80 bar 8 at a point considerably farther back from shoulder 9. The rear end of bar 8 should be closer to bar 11 than its forward end, and must be pivotally connected to bar 11 by a pair of links 17. These links 17, 85

like forward links 14, pass on either side of bars 8 and 11 and are pivotally connected thereto by pintles 18 and 19. Links 17 extend upwardly beyond their connection to bar 8 to form a bearing point 20 for operating lever 21 having a handle 22 by means of which the required pressure may be imparted to the device when positioning the same in gripping engagement with the grain door 7.

Lever 21 is angled, as shown in Fig. 1 to permit its forward end to engage bar 8 through the means of roller 23 which is guided along the upper edge of bar 8 by depending integral walls 24. Angled lugs 25 and 26 forming a part of bar 8 and lever 21 respectively, retain the proper relation between said lever and said bar. A pair of link members 27 which are also pivotally mounted at their lower ends upon pintle 16 bear against transverse pintle 28 and pass between said pin and shoulder 9 to a

100

105

110

point above said shoulder where they are connected by a pin 29 which is adapted to receive one end of a hoisting chain 30, the other end of which is attached by yoke 31 to operating lever 21. This hoisting chain 30 is preferably provided with a series of larger links 32 which may be utilized for engaging the hook of any hoisting means.

Operation.

To operate the grain door puller, shoulder 9 and flange 10 are first placed in engagement with the upper edge and back of grain door 7. Spur 12 is then brought into engagement with the front face of the grain door and caused to positively grip the same by a downward pressure on handle 22 and preferably also by striking surface 13 a sharp blow with a hammer. This action forces spur 12 into the grain door. Operating lever 21 is now lifted up through the means of handle 22 or chain 30 which causes roller 23 to move backwardly and downwardly along bar 8, thereby carrying the upper end of links 17 to the rear. Links 17 pivoted as they are at 18, will obviously have their lowermost end urged forwardly to maintain spur 12 to remain in engagement with door 7. The continued upward pressure either on handle 22 or that part of chain 30 connected to yoke 31, and because of the fact chain 30 connected to point 29 has not as yet been drawn tight, an inward pressure will be brought to bear along bar 8 and through shoulder 9 to the upper edge of grain door 7. This thrust forces the top of grain door 7 away from post 6 and causes all parts of chain 30 to tighten. The end of the door to which the puller is applied is then raised the desired height which breaks loose the opposite end of said door and permits its being removed from the car.

Having thus described the invention, what I claim is:

1. A grain door puller comprising, in combination, means for gripping one edge of the grain door, means for engaging the surface of said door, links connecting said gripping and engaging means, and means for receiving a lifting power said engaging means having a striking head whereby the same is caused to penetrate the surface of said grain door.

2. A grain door puller comprising, in combination, means for gripping the upper edge of the grain door, means for engaging the surface of said door adjacent the bottom edge, toggle-links connecting said gripping and engaging means, and means for applying a lifting power to said puller said upper edge gripping means having a widened shoulder and a depending flange for positive engagement with the upper edge and back of said grain door.

3. A grain door puller comprising, in com-

bination, means for gripping the upper edge of the grain door, means for engaging the surface of said door at a point below said upper edge, links connecting said gripping and engaging means, and an operating means pivotally mounted on one of said links and slidably engaging said gripping means, whereby the grip on said door may be tightened.

4. A grain door puller comprising, in combination, means for gripping the upper edge of the grain door, said means having a depending flange for bearing against the rear surface of said door, means for engaging the front surface of said door, links connecting said gripping and engaging means one of said links being mounted for uninterrupted slidable engagement with said gripping means, and means for simultaneously urging said gripping and engaging means into tighter engagement with said grain door.

5. A grain door puller comprising, in combination, means for gripping the upper edge of the grain door, said means having a depending flange for bearing against the rear surface of said door, means for engaging the front surface of said door including a spur adapted to be forced into said door at a point below and in vertical alignment with said gripping means, links connecting said gripping and engaging means one of said links having its one end pivotally mounted adjacent said spur, the other end thereof projecting beyond and slidably mounted between said upper edge gripping means and a transverse pin carried thereby, and means for applying power to said links.

6. In a grain door puller, means for simultaneously gripping the upper edge of the grain door and engaging the face thereof, means for maintaining said means in operative position comprising a lever having a portion thereof in substantially parallel relation to said upper edge engaging means, said lever and said engaging means having co-acting lugs in engagement with each other, said maintaining means being adapted to increase the grip on said door as it is being dislodged by force exerted through said maintaining means and as said lugs are being disengaged.

7. In a grain door puller, a pair of bars disposed at angles to each other, each bar having grain door engaging means, links connecting said bars, and an operating lever pivotally carried by one of said links and adapted to ride over the upper surface of one of said bars as the puller is being operated.

8. In a grain door puller, a pair of bars disposed at angles to each other and in the same vertical plane, gripping means integral with each of said bars, links pivotally con-

necting said bars in their angular relation and maintaining the same in spaced disconnected relation to each other, and an operating arm pivotally supported by one of said links having means for maintaining said bars in their proper relation.

9. In a grain door puller, a pair of bars having gripping means integral therewith, links connecting said bars adjacent their

ends, and an operating lever pivotally supported by the rear link, said operating lever having its forward end bifurcated and carrying a roller adapted to ride over the upper edge of one of said bars when force is being imparted to said grain door puller.

In testimony whereof I hereunto affix my signature this 17 day of January, 1925.

ADELBERT CHANDLER.
